UNITED STATES PATENT OFFICE.

JOSEPH LIPKEY, OF CHICAGO, ILLINOIS.

COLLAR-PROTECTOR.

1,184,188.

Specification of Letters Patent.

Patented May 23, 1916.

Application filed March 17, 1915. Serial No. 14,942.

To all whom it may concern:

Be it known that I, JOSEPH LIPKEY, a citizen of the United States, and a resident of the city of Chicago, county of Cook, and 5 State of Illinois, have invented certain new and useful Improvements in Collar-Protectors, of which the following is a specification.

My invention relates to a collar protector 10 designed for attachment particularly to an overcoat in order to prevent the ordinary starched shirt collar from being soiled by contact with the inside of the collar of the coat which may be used by the wearer of 15 the collar.

The object of my invention is the production of a construction as mentioned which will be of neat and finished appearance and which will afford a receptacle for 20 the collar protecting element when not in use.

A further object is the production of an arrangement which will be of simple construction, and one which may be applied 25 to a coat already in use or which may be applied to a coat in the making of the same.

Other objects will appear hereinafter.

With these objects in view, my invention consists in the combinations and arrangements of parts hereinafter described and 30 claimed.

The invention will be best understood by reference to the accompanying drawing forming a part of this specification, and in 35 which,

Figure 1 is a fragmental front elevation of the collar portion of an overcoat equipped with a collar protector embodying the invention, Fig. 2 is a detail section taken on 40 line $x-x$ of Fig. 1, and Fig. 3 is a view similar to Fig. 2 showing the collar protector in extended or operative position.

The preferred form of construction as 45 illustrated in the drawing is applied to an overcoat and consists of a pocket which is interposed between the lining 1 of the coat and the body 2 thereof parallel with and adjacent the collar and lapels of the coat. This pocket consists of side walls 3 and 4 50 which are stitched together at their inner edges as at 5. The outer edge of the pocket portion 3 is secured by stitching 6 to the coat lining 1, the corresponding edge of the pocket portion 4 being secured by stitching 7 to the body 2 of the coat. With 55 this arrangement it will be seen that an

elongated pocket is formed at the inner side of the coat having a coextensive elongated mouth or opening which extends parallel with and in close proximity to the collar and lapels of the coat. In practice the pocket portion 4 will be fastened securely in position so as to prevent the pocket being turned inside out, by the central seam ordinarily formed in the back of a coat and by 60 the seams formed at the shoulders of a coat. It is of course understood that if desired or found necessary the pocket may be anchored at other points so as to securely hold the same in position under the lining. 70

Provided in the bottom of the pocket is an elongated coextensive narrow strip 8 which is secured in position at its inner edge by the stitching 5. The strip 8 serves as an anchoring means for the protecting 75 element 9 which is detachably secured at its inner edge to the strip 8 by buttons 10. The protecting element 9 is coextensive in length with the pocket and is of such width as to permit of the outer edge thereof being 80 extended from the pocket so as to be folded over the edge of the collar and lapels of the inside or under coat of the wearer, as clearly shown in Fig. 3, the under coat being indicated in this figure in dotted lines. 85 This being so the member 9 will serve as a protection for the starched linen shirt collar preventing soiling through contact thereof with the coat collar or lapels. By reason of the detachable connection of the member 9 with the anchoring strip 8, when the former has become soiled the same may be 90 readily detached for washing. When the protecting element is not in use the same may be readily and easily folded to position in the pocket as clearly shown in Fig. 2. Buttons 11 are also provided at suitable points to lock the mouth of the pocket in closed condition when the protecting element is folded to position therein. 95

With the construction set forth, it will be seen that when the protecting element is folded to position in the pocket and the latter has been locked by the buttons 11, the presence of the pocket or protecting element in the coat will be unnoticed except for the exposure of the inconspicuous buttons 11. The ends of the pocket as well as the protecting element may be extended down along the lapels or the front edges of 110 the coat to any point desired.

While I have illustrated and described

the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

10 Having described my invention what I claim as new and desire to secure by Letters Patent is:

15 1. The combination of a coat; a pocket provided in said coat adjacent the collar thereof; an anchoring strip provided in the bottom of said pocket; and a protector element having one edge connected to said anchoring strip, the opposite edge of said protector being adapted to be folded to posi-

tion in said pocket or extended therefrom, 20 substantially as described.

2. The combination of a coat; a pocket provided in said coat adjacent the collar thereof; an anchoring strip provided in the bottom of said pocket; and a protector element having one edge buttoned to one side of said anchoring strip, the opposite edge of said element being adapted to be folded to position in said pocket or extended therefrom, substantially as described. 25

30 In testimony whereof I have signed my name to this specification in the presence of two subscribing witnesses.

JOSEPH LIPKEY.
